(57) **CLAIM**

The ornamental design for an enclosure for an electronic device, as shown and described.

DESCRIPTION

FIG. 1 is a front view of the enclosure for an electronic device;

FIG. 2 is a front top perspective view thereof; and, FIG. 3 is another front top perspective view thereof. The broken lines shown in FIGS. 1-8 represent environmental subject matter for illustrative purposes, and form no part of the claimed design. Regions in FIGS. 2, 7, and 8 with evenly spaced parallel lines having a graduated brightness from bottom to top represent an illuminated portion.
